[57] **CLAIM**

The ornamental design for a housing for an electronic instructional game apparatus, as shown and described.

DESCRIPTION

FIG. 1 is a perspective view of a housing for an electronic instructional game apparatus showing our new designs; with some of the insertable blocks removed for clarity of illustration;

FIG. 2 is a top plan view thereof;

FIG. 3 is a rear elevational view thereof;

FIG. 4 is a front elevational view thereof;

FIG. 5 is a left side elevational view thereof;

FIG. 6 is a right side elevational view thereof; and,

FIG. 7 is a bottom view thereof.
